CALCULATING MACHINE

Edwin F. Britten, Jr., Short Hills, N. J., assignor
to Gardner Company, Orange, N. J., a corpora-
tion of Delaware

Application April 14, 1936, Serial No. 74,379

8 Claims. (Cl. 197—114)

This invention relates to calculating machines and particularly to paper feeding means therefor wherein there is provided a rotatable platen and line spacing mechanism, an object of the invention being to provide improved means for obtaining fractional adjustments of the platen to the exact printing line independently of the line spacing mechanism. Another object is to provide improved means for obtaining varying line spacing movements of the platen. Other objects and advantages will appear hereinafter.

The invention consists in the novel construction and combination of parts as set forth in the appended claims.

15 In the accompanying drawing,

Figure 1 is a side view of the invention as applied, with parts broken away.

Figure 2 is a similar view with parts removed to show the means for obtaining varying line spacing movements of the platen.

20 Figure 3 is a detail section on the line 3—3, Figure 1.

In the drawing, the numeral 1 designates the usual cylindrical platen, secured to a shaft 2, mounted between suitable frame plates, of which the left hand frame plate 3 only is shown, said shaft having fast thereto the ratchet wheel 4.

In effecting line spacing movements of the platen, it is proposed to employ a bail lever 5, fulcrumed at 6 to the framing, and having link connection 7 with a segment gear 8, the latter meshing with a gear 9 secured to an arm 10, said arm being loosely mounted on the platen shaft 2 and carrying a spring impelled pawl 11, normally clear of said ratchet wheel and adapted to engage the same upon actuation of said lever 5 intermittently by roller 12 of reciprocating arm 13, the latter being reciprocated during each operating cycle of the machine. A spring impelled detent 15 engages the ratchet wheel to hold the line spacing adjustment.

45 Means are provided for obtaining fractional adjustments of the platen to the exact printing line independently of the line spacing mechanism, as follows:

A planular carrier plate or head 16 is rotatably mounted on the platen shaft 2, the detent 15 being pivoted to said head at 17 and having a roller 18 engaging said ratchet wheel, said head 50 having a member 19 carried therewith and engaging said arm 10 to move said arm and the pawl 11 carried thereby in the operation of manipulable means for rotating said head (to be described). Thus in the rotation of said head, the 55 pawl and the detent will rotate therewith and

a fractional adjustment of the platen will be obtained (through the detent) to the exact printing line, whereupon the line spacing mechanism may operate as before in the new positions of the pawl and the detent. The ratchet wheel 4 is a spur wheel, the pawl 11 is reciprocable in the plane of said ratchet wheel, and the detent is movable in said plane.

Means are provided for obtaining varying line spacing movements of the platen, comprising a plate 20, loosely mounted on the platen shaft 2, and having a limit stop (the member 19 aforesaid) engaged by the arm 10 at the end of each return movement thereof, through the medium of spring cushion device 22 carried by said arm, said plate having an arcuate portion provided with a series of notches 23; and a spring impelled latch lever 24 fulcrumed to said carrier head at 25, and having a lug 26 engageable with any one of said notches 23 to hold said plate stationary and vary the position of said limit stop with respect to said pawl, so that the latter will have a varying extent of movement in accord with the adjustment of said plate. The plate 20 is provided with a projection 27 normally engaged by said pawl to hold it clear of the ratchet wheel 4, and the free end of said latch lever and the free end of said detent are connected by a coiled spring 28 which serves the double purpose of impelling the detent toward the ratchet wheel and the latch lever towards the notched plate 20. The segment gear 8 is pivoted to the carrier head 16, and the latter is provided with a limit stop 29 for the pawl at the end of the forward movement thereof to prevent over rotation of the parts.

A manipulable device is provided for adjusting said carrier head 16 rotatably in obtaining fractional adjustments of the platen, comprising a transverse rod 30, rotatably mounted in the framing and having at one end thereof fast thereto an eccentric 31, the strap 32 of which has a link connection 33 with said head, a finger wheel 34 being mounted on said rod at each end thereof. The adjustment is held by a friction disk 35 carried by said eccentric.

40 A coiled spring 36, connected to bail lever 5 serves to return said lever, link 7, segment gear 8, gear 9, arm 10, and pawl 11 to normal position after each intermittent movement thereof.

The carrier head 16 is provided with a slot 37 engaged by screw 38 of the framing to limit the movement of said head in either direction in making fractional adjustments of the platen.

50 I claim:

55 1. In a machine of the character described,

- having a rotatable platen, a line space wheel carried thereby, a head mounted for rotation on the platen shaft, a detent pivoted to said head and engaging said line space wheel, a line space pawl rotatable with said head and normally clear of said wheel, means including a finger wheel for rotating said head together with said detent and said pawl for fractional adjustment of the platen, and means for reciprocating said pawl for line space movement of the platen in any fractional adjustment position thereof; said line space wheel being a spur wheel, and said pawl being reciprocable in the plane of said line space wheel. 5
2. In a machine of the character described, having a rotatable platen, a line space wheel carried thereby, a head mounted for rotation on the platen shaft, a detent pivoted to said head and engaging said line space wheel, a line space pawl rotatable with said head and normally clear of said line space wheel, means including a finger wheel for rotating said head together with said detent and said pawl for fractional adjustment of the platen, and means for reciprocating said pawl for line space movement of the platen in any 10 fractional adjustment position thereof; said head being planular, said line space wheel being a spur ratchet, said pawl being reciprocable in the plane of said ratchet wheel and said detent being movable in the plane of said ratchet wheel. 15
3. In a machine of the character described, having a rotatable platen, a line space wheel carried thereby, a head mounted for rotation on the platen shaft, a detent pivoted to said head and engaging said line space wheel, a line space pawl rotatable with said head and normally clear of said wheel, means including a finger wheel for rotating said head together with said detent and said pawl for fractional adjustment of the platen, and means for reciprocating said pawl for line 20 space movement of the platen in any fractional adjustment position thereof; an arm loose on the platen shaft, said pawl being pivoted to said arm, and said head having a member carried therewith and engaging said arm to move said arm and said pawl in the operation of said means for rotating said head for fractional adjustment of the platen. 25
4. In a machine of the character described, having a rotatable platen, a line space wheel carried thereby, a head mounted for rotation on the platen shaft, a detent pivoted to said head and engaging said line space wheel, a line space pawl rotatable with said head and normally clear of said wheel, means including a finger wheel for rotating said head together with said detent and said pawl for fractional adjustment of the platen, and means for reciprocating said pawl for line 30 space movement of the platen in any fractional adjustment position thereof; an arm loose on the platen shaft, said pawl being pivoted to said arm, said head carrying limit stops for said pawl one of which is a member loose on the platen shaft and having a series of notches and having a cooperating member pivoted to said head and engageable with any one of said notches to vary the line spacing movement of the pawl, said member having a projection to normally hold said pawl clear of said wheel, and said means for reciprocating said pawl including a gear pivoted 35 to said head. 40
5. In a machine of the character described, having a rotatable platen, a line space wheel carried thereby, a head mounted for rotation on the platen shaft, a detent pivoted to said head and engaging said line space wheel, a line space pawl rotatable with said head and normally clear of said wheel, means including a finger wheel for rotating said head together with said detent and said pawl for fractional adjustment 45 of the platen, and means for reciprocating said pawl for line space movement of said platen in any fractional adjustment position thereof; said means for rotating said head for fractional adjustment of the platen comprising a shaft 50 mounted in the stationary framing of the machine, an eccentric fast to said shaft and having a strap and link connection with said head, and a friction disk carried by said eccentric for holding the adjustment. 55
